UNITED STATES PATENT OFFICE.

ALANSON P. BRUSH, OF DETROIT, MICHIGAN.

DUAL IGNITION SYSTEM.

1,139,255.

Specification of Letters Patent. Patented May 11, 1915.

Application filed March 21, 1912. Serial No. 685,237.

To all whom it may concern:

Be it known that I, ALANSON P. BRUSH, a citizen of the United States, residing at Detroit, in the county of Wayne and State 5 of Michigan, have invented a certain new and useful Improvement in Dual Ignition Systems, of which the following is a full, clear, and exact description:

This invention relates to improvements in 10 so-called dual ignition systems, and has for its object the provision of means whereby a multiple cylinder engine equipped with such a system may be started by the ignition of a charge in the proper cylinder without 15 the necessity of cranking or otherwise turning over the engine to produce the igniting spark.

A multiple cylinder internal combustion engine of four or more cylinders will (if 20 the cylinders contain an explosive mixture) usually start itself by the ignition of the mixture in that cylinder, whose piston has last passed the explosion point in its cycle when the engine was stopped. The expression "usually" is used, because in a four 25 cylinder engine, for example, the engine may possibly, though not ordinarily, stop with all of the cranks so nearly on dead center that it cannot be thus started. Or 30 the explosive mixture may produce so weak an explosion, or the friction of the engine may be so great as to prevent this method of starting. Barring these exceptions, however, it is feasible to start internal combustion engines of this type in this way regularly.

The present state of the art is such that it is quite customary to produce the electric ignition current which is distributed to the 40 various cylinders, by means of what is commonly called a magneto,—the electric current when the engine is in normal operation being produced by the power of the engine itself rotating the magneto armature. For starting or for operating the engine at extremely low speeds, it is customary to provide a source of electric current independent of the operation of the engine, such as a storage or chemical or 45 other battery,—it being customary to use this battery current in connection with the magneto interrupting and distributing mechanism,—this system of ignition being commonly called dual as distinguished from 50 what is commonly called the double system,

wherein the battery or starting current is used in connection with an entirely separate apparatus from the magneto involving the use of an additional set of spark plugs, additional transforming coil or coils, and an additional primary current commutator or timer.

The dual system is thus seen to be materially simpler than the double ignition system, but with the construction of the 65 dual system within the limitations imposed by the proper functioning of the magneto and the engine, an engine of four or more cylinders may and frequently does stop in such position that the battery current cannot be successfully used to produce a starting 70 spark in the proper cylinder with the engine at rest.

This invention has to do with a means of 75 correcting this defect, and making the dual system as surely able to produce a starting spark in the proper cylinder as can be done with the double system,—the means for producing this result including, in this instance, a special coupling through which the 80 engine drives the magneto,—the function of this coupling being to permit the magneto armature and with it the distributor shaft, which it drives, being rotated through 85 a part of a revolution in a direction opposite to that in which it normally runs, and means within this coupling device to automatically restore the armature shaft and distributor shaft which it drives to their 90 proper relation to the engine shaft which drives them, either before or after the engine has started. In explanation for the necessity of doing this, be it known that the engine may stop in such position that the primary current interrupter or circuit 95 breaker on the magneto may be in the open position, in which case, without special apparatus not usually provided, the primary circuit cannot be closed at all and no spark can be produced, or the engine may be 100 stopped in such position that, although the circuit breaker is in closed position so that a spark can be produced, the distributor of the secondary or ignition circuit may be in 105 such position that the spark will be produced in the wrong cylinder for starting, in which event the engine will be started in the reverse direction. Both of these possibilities are entirely eliminated, if the magneto armature be rotated backward through 110

an arc greater than the open circuit arc of the circuit breaker, usually approximately ninety degrees, since by doing this the primary circuit, if open, will be closed, or if 5 closed, will be opened. If the circuit be open, the backward rotation will close it, and upon the return of the armature to its normal relation, the circuit so closed will be opened and a spark produced, and since the 10 distributor will be rotated at the same time into its proper relation, the spark will be directed to the proper cylinder, or, if the circuit be closed, the backward rotation will open it and the starting spark will thus be 15 produced, and because of the backward rotation of the distributor shaft will be directed to the proper cylinder for starting.

In the drawings, wherein I have shown one embodiment of my invention, Figure 1 20 is an end elevation of a magneto adapted to be employed in the dual ignition system, and equipped with the main feature of the invention; Fig. 2 is a side elevation of the 25 same, parts being broken away and other parts being in section; Fig. 3 is a diagrammatic representation of a simple form of dual ignition system in which my invention is utilized.

Referring, first, to Fig. 3, it will be seen 30 that the dual ignition system here shown includes two sources of current, namely, the magneto 10 and the battery 11. Either one of these sources may be connected by means of a suitable switch 12 in circuit with 35 an interrupter or circuit breaker 13 which is usually operated directly by the magneto shaft and the primary 14 of an induction coil or a step-up transformer. The secondary 40 of the coil is in this case connected directly to the movable member of a distributor 16, which is operated by the magneto shaft and at a predetermined speed relative thereto, the stationary contacts of the distributor being connected to the spark 45 plugs 17 of the engine, the system here shown being adapted for a four cylinder engine. It will be seen, therefore, that with both the magneto and battery, the same coil, interrupter and distributing mechanism are 50 employed, and hence to start the engine with which this system is associated, it is essential that the interrupter be opened, so as to interrupt the primary circuit, and that the movable member of the distributor be electrically connected to the spark plug of that 55 cylinder in which the ignition should take place to start the engine in the forward direction. However, by my invention, I am enabled to accomplish this result, and to 60 attain the object before mentioned, as will be seen by reference to Figs. 1 and 2, considered in connection with the diagrammatic representation of Fig. 3.

In Figs. 1 and 2, 18 represents the magneto shaft, and 19 the driving shaft which

is aligned with the magneto shaft, and is to be associated with suitable mechanism by which it may be rotated at the proper speed with reference to the crank shaft of the engine with which it is used. In connection 70 with the magneto, I have illustrated in Fig. 2, in a rather conventional and simple manner, the circuit breaker 13, and the distributor 16 previously referred to,—the cam for operating the circuit breaker being mounted 75 directly upon the magneto shaft, and the distributor arm (the rotating element) being mounted upon the distributor shaft which is operated by the magneto shaft by two-to-one reduction gearing. 80

In order that the engine may be started by simply igniting an explosive mixture in the proper cylinder with the battery as the source of current, I provide between the drive shaft 19 and the magneto shaft 18, a 85 flexible coupling which may be designated as a whole by the reference character 20, this coupling being of a nature such that it enables the distributor and circuit breaker (and incidentally the magneto armature) to 90 be turned backward so that the battery primary circuit may be interrupted and a secondary spark produced in the right cylinder. The coupling includes a disk 21 fixed to the drive shaft 19, and a wheel 22 fixed to the 95 magneto shaft 18 and provided with an outwardly projecting flange which surrounds the disk 21. The driving element between the disk 21 and the wheel 22, and hence between the drive shaft and the magneto (and 100 the rotating elements associated therewith) consists of a spiral or volute spring 23, the outer end of which is connected by a pin 24 to the disk 20, and the inner end of which is connected by a pin 25 to the wheel 22. 105 The spring 23 is so tensioned that under normal conditions and during normal operation, the drive shaft 19 and the magneto will substantially preserve their required relationship, but in order that the proper relative positions may be maintained with certainty, an automatic latch is provided for connecting them, and holding them in proper relationship. As shown, this latch includes a radially movable dog or plunger 110 26 mounted within a radial socket of the disk 21. This dog has a conical outer end adapted to be thrown by centrifugal force into a notch in the overlying flange of the wheel 22. With this flexible coupling just 115 described, I am enabled to turn the rotary parts of the circuit breaker and the distributor backward or in the reverse directions to those in which they are normally operated, by simply turning the wheel 22, and after 120 these parts have thus been turned a sufficient distance, the tension stored in the coupling spring during such movement will cause the said parts and the armature of the magneto to be restored to, or substan- 125 130

tially to, their normal positions relative to the drive shaft. The parts will be restored to their proper relative positions after the engine is started, if not before, and will be held in such positions during normal operation by the dog 26. Any suitable means may be utilized for turning the wheel 22 but in this case I have provided for this purpose a disk segment 27 which is mounted upon a shaft 28 carried by a bracket 29 secured to the side of the magneto. The segment 27 has a V-shaped edge which may frictionally engage a V-shaped groove in the periphery of the wheel 22, so that the rotation of the segment through a suitable arc or part of a revolution when frictionally engaging the wheel 22 will cause the wheel 22 to be rotated. The segment may be turned in any desired manner. In this instance the shaft 28 is provided with a crank 30 which may be connected to any suitable operating mechanism which may be actuated by the operator. If the wheel 22 and magneto armature are turned by the segment 27 through a part of a revolution backwardly against the tension of the spring and then released, they will be quickly returned by the spring to their former positions. To limit the movement of these parts under the action of the spring relative to the drive shaft, the disk 21 may be provided with a stop stud 31 adapted to be engaged by a similar stud 32 on the wheel 22.

To render my invention effective, the cylinder in which ignition is desired to start the engine from rest must, of course, contain explosive mixture. This cylinder is the one whose piston has finished its compression stroke and started on what would normally be the explosion or working stroke. This cylinder will contain explosive mixture if the ignition apparatus be cut out of service just before the engine last stopped, so as to leave the charge in said cylinder unexploded; or the cylinder may be primed by any suitable priming apparatus. If, now, the battery is connected to the transforming, interrupting and distributing parts of the system, and if the magneto shaft is turned backward until the interrupter, if previously in closed position, is opened so as to interrupt the primary circuit, or, if previously in open position, is closed so that the subsequent forward movement of the armature shaft under the action of the spring will cause the opening of the circuit breaker and hence of the primary circuit an igniting spark will be produced in the proper cylinder for starting the engine.

It will be understood that after the movement of the segment 27 during which the wheel 22 is frictionally driven by the segment, the latter is moved out of engagement with this wheel so that the armature 65 may be driven in the usual manner by the

drive shaft and in proper relationship therewith.

Having thus described my invention, what I claim is:

1. In a dual ignition system for a multiple cylinder engine, two sources of current comprising a battery and a magneto, the latter having associated therewith a drive shaft adapted to be operated by the engine, circuit interrupting and distributing mechanisms and comprising rotary members adapted to be driven by said drive shaft, and a coupling between the drive shaft and said rotary members by which the latter may be turned relative to the drive shaft 75 when the engine is at rest to interrupt the battery circuit and direct the spark to the proper cylinder for starting the engine in the forward direction.

2. In a dual ignition system for a multiple cylinder engine, two sources of current comprising a battery and a magneto, the latter having associated therewith a drive shaft adapted to be operated by the engine, circuit interrupting, distributing and transforming mechanisms and including rotary circuit breaker and distributor members associated with the magneto so as to be driven thereby, and a flexible coupling between the drive shaft and the magneto by which the latter may be turned backward and thence will be restored to normal position relative to the drive shaft, so that the circuit breaker and distributor will interrupt the primary battery circuit and direct the high tension current to the proper cylinder for starting the engine in the forward direction.

3. In a dual ignition system for a multiple cylinder engine, two sources of current comprising a battery and a magneto, the latter having associated therewith a drive shaft adapted to be operated by the engine, circuit interrupting, distributing and transforming mechanisms including rotary circuit breakers and distributor members associated with the magneto so as to be driven thereby, and a flexible coupling between the drive shaft and magneto including a spring which enables the magneto to be turned backward relative to the drive shaft when the engine is at rest, and thence quickly in a forward direction, so that by moving the circuit breaker and interrupter, the primary battery circuit may be interrupted, and a spark directed to the proper cylinder for starting the engine in the forward direction.

4. In a dual ignition system for a multiple cylinder engine, two sources of current comprising a battery and a magneto, the latter having associated therewith a drive shaft adapted to be operated by the engine, circuit interrupting and distributing mechanisms including rotary circuit breaker and distributor members associated with the

magneto so as to be driven thereby, and a coupling between the drive shaft and the magneto by which the latter may be turned backward and thence restored to normal 5 position relative to the drive shaft so as to cause the primary battery circuit to be interrupted by the circuit breaker and the high tension current directed by the distributor to the proper cylinder for starting the engine 10 in the forward direction, and means for locking the magneto shaft and drive shaft in proper relationship when the engine is in operation.

5. In a dual ignition system for an internal combustion engine, two sources of current comprising a battery and a magneto, the latter having associated therewith a drive shaft adapted to be operated by the engine, circuit interrupting and distribut-

ing mechanisms comprising movable parts 20 adapted to be actuated by the drive shaft, a switch by which either the battery or the magneto may be connected to the interrupting and distributing mechanisms, and a coupling between the drive shaft and circuit 25 interrupting and distributing mechanisms by which the latter may be operated independently of the drive shaft when the engine is at rest so as to interrupt the battery circuit and direct a spark to the proper 30 cylinder for starting the engine in the forward direction.

In testimony whereof, I hereunto affix my signature in the presence of two witnesses.

ALANSON P. BRUSH.
